TEXTILE FABRIC

Henry Rose, New York, N. Y.

Application November 14, 1951, Serial No. 17,382

Term of patent 3½ years

(Cl. D92—1)

To all whom it may concern:

Be it known that I, Henry Rose, a citizen of the United States of America, resident of New York, in the county of New York, and State of New York, have invented a new, original, and ornamental Design for a Textile Fabric, of which the following is a specification, reference being had to the accompanying drawing, forming part thereof.

In the drawing the figure is a plan view of a textile fabric, showing my new design;

A design unit is outlined by dotted lines and is repeated as indicated.

I claim:

The ornamental design for a textile fabric, substantially as shown and described.

HENRY ROSE.
